CLAIM

The ornamental design for a clip for holding a liquid-sample cell in a spectrophotometer, as shown and described.

DESCRIPTION

FIG. 1 is a perspective view of the clip for holding a liquid-sample cell in a spectrophotometer showing our new design;

FIG. 2 is a rear elevational view;

FIG. 3 is a side elevational view;

FIG. 4 is a top plan view; and

FIG. 5 is a bottom plan view.
